SUBMERGED COMBUSTION SYSTEM

Theodore S. See, Hammond, Ind., John Edward Tegarden, Chicago, Ill., and Arthur Williams, Munster, and Walter G. See, Hammond, Ind., assignors to Submerged Combustion Company of America, Inc., Hammond, Ind., a corporation of Indiana

Application April 5, 1943, Serial No. 481,792

8 Claims. (Cl. 158—28)

1

This invention relates to a submerged combustion system and more particularly to a system for the control of submerged combustion burners.

The expression "submerged combustion" is used herein to describe combustion beneath the surface of the liquid in direct contact with the liquid and is to be distinguished from the older methods of heating liquids which involve the transfer of the heat from the products of combustion through a metal wall, as, for example, in a steam boiler.

One of the objects of the invention is to provide a submerged combustion system, including a submerged combustion burner, means for supplying fuel thereto, ignition means for the fuel and motor actuated timer means controlled by the temperature of the liquid to be heated for automatically regulating the fuel supply means and the ignition means.

Another object of the invention is to provide a submerged combustion system including a submerged combustion burner, means for supplying pilot fuel thereto, means for supplying main fuel thereto and motor actuated timer means controlled by the temperature of the liquid which is being heated by the burner for automatically regulating the pilot fuel supply means, the main fuel supply means and the ignition means.

Another object of the invention is to provide a submerged combustion system of the type described including means to prevent the operation of the pilot fuel supply means upon failure of operation of the ignition means.

Still another object of the invention is to provide a new and improved submerged combustion system of the type described, including means to maintain the operation of the pilot fuel supply means for a period after ignition independently of the timer operation.

Still a further object of the invention is to provide a submerged combustion system of the type described including means independent of the timer means to prevent the operation of the main fuel supply means, or both the main fuel supply means and the pilot fuel supply means when the gas pressure is below a predetermined minimum.

An additional object of the invention is to provide a new and improved submerged combustion system of the type described including means to prevent the operation of the main fuel supply means upon failure of operation of the pilot fuel supply means.

Other objects and advantages of the invention will be apparent by reference to the following

2

description in conjunction with the accompanying drawings in which:

5 Figure 1 represents a general layout of one type of submerged combustion burner system which may be employed in the practice of the invention;

10 Figure 2 represents a simplified wiring diagram comprising various circuits utilized in the operation of the submerged burner system shown in Figure 1;

15 Figures 3 to 8, inclusive, represent diagrammatically the operation of the motor actuated timer means employed to control the submerged combustion burner system in accordance with the preferred embodiment of the invention.

20 Referring to Figure 1, the submerged combustion system shown therein comprises a submerged combustion burner, generally shown at 2, which is disposed in a suitable tank 4 containing a liquid 6. As shown, the outer casing 8 of the burner 2 preferably extends downwardly along the inside wall of the tank 4 and branches out at the bottom as an L-shaped member in which the base of the L is formed by the conduit 10. The 25 combustion gases are discharged directly into the liquid 6 through the holes 12, and the discharge of these gases serves to agitate the liquid. Other modifications of the L shape may be used, the principal ones, however, all involving some form 30 of an L shape, such as for example, a U-shape, which is the equivalent of two L's, with the base of one opposite to the base of the other, or a T-shape which is equivalent to two L's with the sides coinciding and the bases of the L's extending in opposite directions. The present invention is not concerned specifically with the form of the submerged burner itself. Various types of burners may be used, such as described, for example, in See et al., U. S. Patent 2,118,479.

40 The principal elements of the burner illustrated in Figure 1, in addition to those previously described, comprise an outer passageway 14 through which the main supply of fuel is introduced, an intermediate passageway 16 through which the 45 main supply of air is introduced, and an inner passageway 18 where the pilot fuel and air are supplied and ignited by means of an igniter indicated at 20. The main fuel and air supplies pass through a burner plate 22 provided with suitable holes and are ignited by the pilot flame passing downwardly through the inner passageway 18, thereby causing the main combustion to take place at or beyond the burner plate 22 in direct contact with the liquid 6.

50 As will be understood, the air and fuel must be

supplied at pressures great enough to overcome the head of the liquid. The air is supplied in the system shown in Figure 1 by means of a blower generally illustrated at 24. The air is taken into the blower through an air cleaner 28, from which it passes through conduit 28 into the blower and is then forced through conduit 30 and a conduit 36. From conduit 36 a minor proportion of the air is forced through conduit 38 and is referred to herein as the pilot air supply. Most of the air, however, continues through conduit 40 and is introduced into the passageway 16 of the burner 2.

The pilot air flows through pilot air control valve 42, a measuring orifice 46, and through the pilot air line into the burner head wherein it passes around the pilot tube 44 and thence into the pilot manifold 18. Shut off cocks 48 are provided on each side of measuring orifice 46 so that a manometer can be easily connected when desired in order to determine the pilot air flow.

A bypass governor 50 controls the gas supply so that its pressure is the same as that of the air supply and also permits the compressed gas to flow from the high pressure or exhaust side of the gas compressor 52 through the governor back to the low pressure or intake side via conduit 54 when the solution or liquid 6 is at the proper temperature and the gas control valves, hereinafter described, are in closed position so as to stop any gas flow to the burner. The equalization of pressure between the gas and air supply is maintained by pressure equalizing lines 56 and 58. In case the gas pressure is sufficiently high so that a gas compressor is not required, it will be understood that a different type of governor may be used and that the bypass arrangement 54 will not be necessary. A gas strainer 60 is provided and should be periodically washed and cleaned. If gas is available at a pressure sufficiently high to overcome the resistance due to the head of solution in the tank 4, the gas-main is connected directly to the governor 50.

From the governor 50 the gas is passed through a gas supply pipe 62 and one part, the pilot gas, passes through a conduit 64 controlled by a solenoid actuated valve 66, the other part, which forms the main gas supply, passing through conduit 68 controlled by a solenoid actuated valve 70. Conduit 68 is provided with a measuring orifice 72 to control the flow of gas and may be provided on either side of said orifice with suitable cocks, not shown, similar to cocks 48 to which a manometer may be attached to determine the gas pressure. A manually controlled valve 74 is also provided to control the main gas flow. The main gas supply flows through conduit 68 and enters the passageway 14, from which it passes through the burner plate 22 for combustion with the main air supply flowing through the annular passageway 16.

The pilot fuel supply flows through conduit 64, manually controlled pilot gas control valve 76, measuring orifice 78, and is conducted to the igniter 20 through pilot gas tube 44. It will be understood that the igniter may be above the liquid level, as shown, at the liquid level, or below it. A sight port is provided at 80 to view the flames if desired. A pair of cocks 82 are provided for a manometer which can be used if necessary to determine the gas flow through the conduit 64.

The igniter 20 consists of a wire which becomes red hot when heated by a source of electrical energy supplied through a conductor 84. The conductor 84 is preferably run through the

inside of the pilot air supply conduit 36 which it enters at point 88, through a suitable packing box or connection chamber 90, the latter being connected to a cable 92 carrying the conductor 84. The cable 92 in turn is connected to a suitable step-down transformer generally indicated at 94. The step-down transformer 94 receives its current from a high voltage line, as described in Figure 2. Also shown in Figure 1 is a constant current transformer 96, which preferably consists of a 3-pillar laminated iron core with a stationary low voltage secondary coil below, and a floating 110 volt primary coil above, both of which are mounted around the central pillar. Any variations in line voltage within 25% above or below normal change the position of the primary coil but will not change the secondary ignition current. An additional step-down transformer 32 is supplied for the timer control circuit. A control box 98 houses transformer 32 and most of the control elements which will be described more fully hereinafter with reference to Figure 2. The operation of the system is also controlled in response to the temperature of the liquid 6 by means of a thermostatic element 100 connected through a line 102 and capable of actuating a switch 104, which in turn closes a circuit to initiate a cycle of operations in the manner hereinafter described. The controlling push buttons 106 are generally indicated at 106, 106' the adjustment for the thermostatic control at 108, the high voltage line carrying the source of electrical energy at 110, and the line carrying the source of electrical energy to the compressors 24 and 52 at 112.

The burner system previously described is controlled electrically in a manner which may be best understood by reference to Figure 2. As shown in Figure 2, a source of electrical energy (of any type which is required to drive the motor 114) is passed through the lines or conductors L¹, L², and L³ to a motor 114 which serves to drive the blower 24, or both the blower 24 and the gas compressor 52 if a compressor is necessary. The motor is started by pressing the start button indicated at 106 which serves to energize a solenoid M, of a relay switch 111, thus closing and holding closed the contacts M¹, M², M³, and M⁴ of said relay switch. An overload relay OL is provided to protect the motor from overloading and to break the circuit through the solenoid M by breaking the contacts OL₁ when an overload occurs, otherwise the contacts OL₁ are normally closed as illustrated. The motor control circuit thus extends from one side of the secondary winding of the transformer 32 through a fuse F₅, the normally closed stop switch 106', the start switch 106, the solenoid M of relay switch 111, the overload switch OL₁, and thence back to the other side of the secondary winding of the transformer 32, through a return conductor C₂ which is preferably grounded. Thus, it will be seen that when the starter button at 106 is pressed the motor 114 runs continuously, thereby driving the air compressor and the gas compressor and causing a constant volume of air to pass through the burner thereby continuously agitating the liquid 6 regardless of whether the fuel has been ignited or the liquid is being heated.

As shown in Figure 2, the lines L¹ and L³ have takeoffs to the transformer 32 which transforms the current from a voltage of 500 volts to 110 volts. The 110 volt circuits are grounded at G' and one side of the line passes through the 75 starter button at 106, and the holding switch

contacts M^4 , which remains closed to maintain the circuit through coil M even after the start button opens when released after being pressed down to start the system in operation. The timer circuit also passes through the manually operable off and on switch 118 , which is normally closed, and the thermostat switch 104 , which is closed if the temperature of the liquid 6 is below the thermostatic setting. From the thermostat 104 the current passes through a conductor c_1 to a motor actuated timer generally indicated at 120 in Figure 2. The invention is not limited to the use of any particular motor actuated timer but may be illustrated by reference to a timer of the type described in U. S. Patent 2,175,864. The principal elements of this type of timer are shown diagrammatically in Figures 3 to 8. These Figures 3 to 8 also show the various positions of the various elements of the timer at different stages of the submerged combustion control operation, and these various positions of said elements, together with the operation thereof, will be described hereinafter.

The current flowing through conductor c_1 energizes the timer motor 122 in a manner which will be hereinafter described and the other side of the line returns to the transformer 32 through the grounded conductor c_2 . As will be observed, a portion of the current from the conductor c_1 is connected through a coil G which operates a clutch associated with the timer 120 , as hereinafter described.

Another circuit may be traced from the thermostat switch 104 through conductor c_3 , contacts T^1 of timer 120 , contacts ISR_1 of relay switch ISR , conductor c_4 , the coil of a control relay $2CR$, and thence through the grounded conductor c_2 to complete the circuits.

Also, as shown in Figure 2 a return circuit may be traced from thermostat switch 104 through conductor c_3 , contacts $2CR_1$ of control relay $2CR$, conductor c_5 and thence either through conductor c_6 and the coil of control relay $2CR$ directly to the return side of the circuit, or through conductor c_7 and the coil of solenoid actuated pilot gas valve 66 to the return side of the circuit comprising the conductor c_2 .

Another circuit may be traced from thermostat switch 104 through conductor c_3 , timer contacts T^2 , contacts $2CR_2$ of control relay $2CR$, contacts P^1 and P^2 of gas pressure safety switches, which would be normally placed ahead of drainage trap 60 , of Figure 1, in the gas supply line 34 , conductor c_8 , and the coil of solenoid actuated main gas valve 70 to the conductor c_2 comprising the return side of the circuit.

Another circuit may be traced from the thermostat switch 104 through conductor c_3 , timer contacts T^3 , conductor c_9 , and the coil of a control relay ICR to the return conductor c_2 .

Fuses are provided at various places in the various circuits at F^1 , F^2 , F^3 , F^4 , and F^5 for safety purposes, as will be readily understood. Certain other devices and safety precautions may be provided without departing from the invention. For example, pressure switches like the switches P^1 and P^2 may also be placed in the conductor c_7 ahead of the pilot gas valve 66 thereby to break the flow of gas to the pilot valve in the event that the gas pressure is too low.

As will be observed from Figure 2, the gas pressure safety switches P^1 and P^2 are normally closed and the same is true with respect to the contact OL_1 of the overload relay OL . If the gas pressure is too low, contacts P^1 and P^2 will

open, breaking the circuit through the main gas valve 70 and causing the latter to close. If the motor 114 burns out, the overload will cause contacts OL_1 to open, breaking the circuit through the coil M and shutting down the entire apparatus. All of the other contacts are shown in a normally open position, which is the position they occupy when the apparatus is entirely out of operation. However, it will be understood that after the push button 106 has been pressed to start the system in operation the contacts M^1 , M^2 , M^3 , and M^4 will be closed by the coil M and will remain closed until the "stop" button at $106'$ is pressed or until the circuit is broken through the coil M in some other manner, as by operation of the overload relay OL , as previously explained.

The thermostat switch 104 is shown with the contacts normally closed which assumes that the liquid to be heated is below the temperature desired at the time the start button 106 is pressed. The timer contacts T and T^3 are shown as normally open, but it should be understood, as will be hereinafter explained, that just as soon as coil G is energized, as shown in Fig. 4, the timer mechanism is released and contacts T and T^3 assume a closed position, thereby causing the timer motor 122 to be energized and at the same time energizing the coil of the control relay ICR . The coil G is energized from the secondary winding of the transformer 32 , upon closure of the start switch 106 , provided that the thermal switch 104 and the main switch 118 are in closed position. After being thus initially energized by the closure of the start switch 106 , the coil G will be maintained in energized condition through the closure of switch contacts M^4 , until said contacts open as a result of the operation of the stop switch $106'$.

When the coil of the control relay ICR is energized it closes the contacts ICR_1 and ICR_2 , thereby causing the transformers 94 and 96 to be energized, which in turn causes a flow of electrical energy to the hot wire igniter 20 . Thus, the ignition transformer circuit can not be energized prior to the energization of the timer motor 122 , and hence the opening of the gas valves 66 and 70 will be prevented until the igniter is operating.

As will be observed, the energization of the ignition transformer circuit also causes the coil of series relay ISR to be energized, thereby closing contacts ISR_1 . At such time the timer motor 122 is in operation, and after a predetermined interval will close contacts T^1 , as shown in Fig. 5. If the ignition transformer circuit, for any reason, has not previously been energized, relay contacts ISR_1 will be open and nothing can happen in the circuit controlled by the contacts T^1 . Thus, the series relay ISR provides means to prevent the operation of the pilot fuel supply means and subsequent operation of the main fuel supply means if there has been a failure in the electrical system of the igniter. If the igniter is operating satisfactorily, however, the contacts ISR_1 will be closed and the circuit through the coil of control relay $2CR$ will be energized upon the closing of the timer contacts T^1 by the timer motor. At the same time the circuit through the conductors c_6 , c_7 , and the solenoid of pilot gas valve 66 will be energized, opening the pilot gas valve and permitting a flow of pilot gas past the igniter 20 , which will thereupon ignite the gas. It will be understood that the timer motor is set to allow a predetermined time interval between the energization of the igniter circuit and the closing of

the timer contacts T^1 to energize the pilot gas valve circuit.

As soon as control relay 2CR is energized it will close the contacts 2CR₁ in the pilot gas valve circuit and thereby provide means to maintain the operation of the pilot fuel supply for a period after ignition independently of the timer. Closure of the contacts 2CR₁ also serves to energize the relay 2CR through the conductor c_6 . Thus, the subsequent opening or closing of the timer contacts T^1 no longer affects the operation of the pilot gas valve 66.

The control relay 2CR when energized also closes relay contacts 2CR₂ in the main gas valve circuit and after a predetermined interval, when timer contacts T^2 are closed by further operation of the timer motor 122, as shown in Fig. 6, the solenoid of the main gas valve 70 will be energized, thereby permitting free flow of the main gas supply to the burner, as previously described. The pilot gas valve also continues to remain open and both gas valves will remain open until the circuit is broken through their respective solenoids, which may be accomplished either by opening the thermostat switch contacts 104, or the manual switch 118, or the stop switch at 106, or by opening the timer contacts T^2 , or by opening the gas pressure safety switches P¹ and P². Since it is essential that the system should remain in operation until the liquid reaches a desired temperature and, to this end, that the main gas valve shall remain open, contacts T^2 should remain closed even though the timer motor contacts T be opened by the timer motor to disable the same. Before the timer motor is stopped, however, the timer contacts T^3 are opened, as shown in Fig. 7, so that the coil of control relay 1CR is de-energized, and the ignition system is thereby de-energized by the opening of relay contacts 1CR₁ and 1CR₂. The relay 1SR also becomes de-energized, thus opening relay contacts 1SR₁ and restoring a part of the circuit through the pilot gas valve to its initial position. The opening of the contacts T^3 to de-energize the ignition circuit may be accomplished either prior to or simultaneously with the opening of the motor contacts T. However, after the timer motor 122 is stopped, with the timer contacts T^2 closed, the apparatus will continue to supply gas to the burner for combustion beneath the surface of the liquid so long as the thermostat calls for heat. When the thermostat switch 104 opens, the fuel supply system will automatically shut down because the solenoid valves 66 and 70, respectively, of the pilot fuel supply means and the main fuel supply means, will both be de-energized. The clutch coil G of the timer motor is also de-energized and the timer mechanism is reset to its initial position by a suitable spring in which energy has been stored by the operation of the timer motor, as hereinafter explained. As a result, all of the timer contacts T, T^1 , T^2 and T^3 will be restored to their original open positions when the switch 104 opens. When the thermostat switch is again closed, due to a falling temperature in the liquid, the operation will be repeated. If it is desired merely to run the blower motor 114 and to disconnect the burner, this may be accomplished by opening switch 118. Normally, however, the entire system will remain energized and the burner operation will be subject to the opening and closing of the thermostat switch 104.

The timer mechanism employed in combination with the other elements, as previously de-

scribed, does not per se form a part of this invention and it will be understood that various types of timer mechanisms may be employed in the practice of the invention. As an example of a timer mechanism which may be used, reference is made to U. S. Patent 2,175,864 which discloses such a mechanism although not in a combination of this type. For the sake of clarity, the details of said mechanism will not be given here except so far as is necessary to understand the application of this mechanism to the present invention. The operation of the timer mechanism is illustrated herein in Figures 3 to 8, inclusive, and may be described as follows.

15 Preferably the elements of the timer mechanism include a timer motor 122, a latching device LA, a spring S connected to the latching device, a clutch CL, a clutch spring S¹, the clutch coil G previously referred to, a third spring S², 20 four sets of contacts T, T^1 , T^2 , and T^3 , also previously referred to, and means to open and close said contacts represented by the cam elements C, C¹, C², C³, C⁴, C⁵, C⁶, and C⁷ against which the contacts are biased by means of a suitable spring, 25 not shown. A stop ST is also provided to limit the movement of the latch mechanism LA. The cam members C to C⁷ have been represented as being carried by a shaft SH, which is driven by the timer motor 122 through the clutch CL.

30 In Figure 3 the timer mechanism is shown with the timer motor de-energized. In this position the spring S holds the latch bar LA against the stop ST and the stops n hold the contacts T, T^1 , T^2 , and T^3 away from each other irrespective 35 of the positions of the cams C to C⁷. In this position, as previously explained, the clutch coil G is also de-energized, and as shown the clutch is held open by spring S¹. The spring S² is in its normal uncoiled position with respect to the drum 40 or pulley D. When the clutch coil G is energized in the manner previously explained with respect to Figure 2 it moves the bar B against the pressure of spring S¹ to cause the clutch CL to engage and simultaneously unlatches the latch bar LA, 45 moving it against the pressure of the spring S and causing the stops n to disengage and permit the contacts T, T^1 , T^2 , and T^3 to assume their normally biased positions against the cams C to C⁷, as illustrated in Figure 4. Since the 50 cams C to C⁷ are so positioned that the contacts T and T^3 are then closed, the timer motor will start immediately upon the closing of contacts T and will begin to drive the shaft SH through the clutch CL and store energy in the spring S² by winding it around the drum D, as shown, or 55 in any other suitable manner. The driving of the shaft SH will cause a rotation or other movement of the cam surfaces C to C⁷, and as these cams move to various positions the contacts will be opened or closed in the manner previously explained with reference to Figure 2.

As shown in Figure 5, the next operation of the timer is the closing of contacts T^1 which causes the opening of the pilot gas solenoid valve 66 in the manner previously explained. At this point contacts T, T^1 , and T^3 are all closed but contacts T^2 which control the main gas supply are still open, thus giving an opportunity for the pilot gas 60 to ignite ahead of the main gas.

The next step is the closing of contacts T^2 , which is illustrated in Figure 6 wherein all of the contacts are closed. The closing of contacts T^2 opens the main gas valve 70 and places the burner in full operation until the thermostat 75

switch 104 opens (Figure 2) and breaks the motor circuit through conductors c₁ and c₂.

While the burner is in full operation the ignition system is no longer necessary, so that the contacts T³ controlling the ignition system may be opened as shown in Figure 7. Finally, after the burner has been placed in full operation, it is also necessary to stop the operation of the timer motor in order to keep the contacts T¹ and T² closed, and this is accomplished by opening the motor contacts T, so that when the burner is in full operation the various elements of the timer will assume the positions shown in Figure 8. In the positions shown in Figure 8 the clutch coil G is still energized but the timer motor 122 is no longer running. The clutch is strong enough to hold the shaft SH against the tendency of the spring S² to restore to its initial position. The latch bar LA is still held in unlatched position due to the fact that the coil G is still energized. As soon as the coil G is de-energized by the opening of the thermostat switch 104 (Figure 2) the clutch CL will disengage due to the spring S¹ and the latch bar LA will simultaneously move to the left, locking the contacts T, T¹, T², and T³ away from the cams C to C⁷ and thereby permitting the spring S² to restore to its initial position and at the same time move the shaft SH to cause the cams C to C⁷ to restore to their initial positions, all as shown in Figure 1. As soon as the thermostat calls for heat, the cycle is repeated in the manner already described.

It will be understood that the description of the timer mechanism is merely for the purpose of illustration and that the elements thereof do not necessarily have the appearance of the illustrative elements used in Figures 3 to 8. Thus, the cams C to C⁷ are not in fact cam wheels in the specific apparatus described in U. S. Patent No. 2,175,864, but instead perform the function of the plate (82). Nevertheless, the cams could replace the plate and have been used in order to clarify the description.

It will be understood that the positions of the cams C to C⁷ shown in Figures 3 to 8 are approximate for the purpose of illustration only and may be varied to suit the particular desired timing relationship. Thus, the cams may be varied not only as to the cam surface but as to the size of the cams.

The invention is of importance because it provides a new and improved submerged combustion system in which the operating parts are relatively simple and in which the operation is safe and satisfactory. Systems of this type may be used for many purposes, for example, in heating pickling baths for steel pickling operations, for evaporation, water softening, and for other purposes to which submerged combustion is applicable.

Having thus described the invention, what we claim as new and desire to secure by Letters Patent of the United States is:

1. A submerged combustion system comprising a liquid submerged combustion burner; fuel supply means for delivering fuel to the burner, including fuel supply conduit means and electrically operated fuel flow control means; ignition means for igniting the fuel; electrical control means adapted for connection with a suitable source of energizing power, for operating said flow control means and said ignition means in a predetermined time delayed sequence; said electrical control means comprising an operating circuit for said flow control means including a control switch

for controlling the operation of said flow control means, a control circuit including an igniter timing switch for operating said ignition means, timer means operable initially to close said igniter timing switch, relay means operable by said timer means following closure of said igniter timing switch to thereafter close said control switch, and thermally responsive switch means responsive to the temperature of the liquid to be heated for selectively rendering said electrical control means operative or inoperative.

2. A submerged combustion system as set forth in claim 1 wherein said electrical control means includes an additional timing switch operable by said timer means to energize said operating circuit after a predetermined time-delay interval following closure of said igniter timer switch.

3. A submerged combustion system as set forth in claim 1 wherein said electrical control means includes an additional timing switch operable by said timer means to energize said operating circuit after a predetermined time-delay interval following closure of said igniter timing switch, said timer means being operable thereafter to open said igniter timing switch to disable said ignition means, and means to maintain said valve operating circuit after the igniter switch has opened.

4. A submerged combustion system as set forth in claim 1 wherein said electrical control means includes an additional timing switch operable by said timer means to energize said operating circuit after a predetermined time-delay interval following closure of said igniter timing switch, a driving motor selectively clutchable with said timing means to drive the same, said timing means being operable to stop said motor, after said operating circuit has been energized, with the timing means in cocked position maintaining said operating circuit, and means operable to release said timer means for return from cocked to standby position upon disconnection of the electrical control means from the energizing power source.

5. A submerged combustion system as set forth in claim 1 wherein said electrical control means includes an additional timing switch operable by said timer means to energize said operating circuit after a predetermined time-delay interval following closure of said igniter timing switch, a driving motor selectively clutchable with said timing means to drive the same, said timing means being operable to stop said motor after said operating circuit has been energized, with the timing means in cocked position maintaining said operating circuit, and means operable to release said timer means for return from cocked to standby position upon failure of the fuel supply.

6. A submerged combustion system as set forth in claim 1 wherein said electrical control means includes an additional timing switch operable by said timer means to energize said operating circuit after a predetermined time-delay interval following closure of said igniter timing switch, a driving motor selectively clutchable with said timing means to drive the same, said timing means being operable to stop said motor after said operating circuit has been energized, with the timing means in cocked position maintaining said operating circuit, and means operable to release said timer means for return from cocked to standby position upon failure of the fuel supply, said means comprising normally closed low pressure switch means in said operating circuit and

adapted to open when pressure of the fuel supply falls below a predetermined value.

7. A submerged combustion system, as set forth in claim 1, including safety switch means in said operating circuit and actuated in response to the operation of said ignition means to prevent operation of said relay means in the event of failure of the ignition means to function.

8. A submerged combustion system comprising a liquid submerged combustion burner, pilot fuel supply means and main fuel supply means for delivering pilot fuel and main fuel to the burner, including pilot fuel and main fuel supply conduit means, and electrically operated pilot and main fuel flow control means operatively associated, respectively, with said pilot and main fuel supply conduit means; ignition means for igniting the fuel supplied at said burner; electrical control means for operating said pilot and main fuel flow control means and said ignition means in a predetermined time delayed sequence, said electrical control means comprising an operating circuit for said pilot fuel flow control means, said operating circuit including a control switch for controlling the operation of said pilot fuel flow control means, an operating circuit for said main fuel flow control means, said last named operating circuit including a control switch for controlling the operation of said main fuel flow control means, timer means operable to close a plurality of timing switches, respectively, in a predetermined sequential order, control circuit means including a first of said timing switches for operating said ignition means, circuit control means for controlling the pilot flow control means

5

and including a second of said timing switches, circuit control means for controlling the main fuel control means and including a third of said timing switches, and means responsive to energization of said ignition means for preparing the pilot circuit control means, said first, second, and third switches being actuated in sequence, whereby upon operation of the timer means the ignition means, pilot fuel supply means and main fuel supply means are sequentially operated.
